VANITY CASE

Percy J. Callowhill, Providence, R. I., assignor to
 Hurst Incorporated, Boston, Mass., a corpora-
 tion of Massachusetts

Application April 26, 1935, Serial No. 18,434

12 Claims. (Cl. 132—83)

This invention relates to certain new and useful improvements in vanity cases.

The primary object of the invention is to provide a vanity case having a hinged cover with a powder compartment in the case adapted to be covered and closed by a hinged mirror within the case with means forming a connection between the hinged mirror and hinged cover to effect shifting movement of the mirror to a position ready for use when the cover of the case is open.

A further object of the invention is to provide a vanity case of the foregoing character wherein the connecting means between the hinged mirror and hinged cover in the vanity case is in the form of a leaf spring that is adapted to be placed under tension when the cover is closed to cause the mirror to seal the powder compartment when the case is out of use to prevent the escape of powder from the compartment.

A still further object of the invention is to provide a vanity case embodying a frame structure including powder and rouge compartments with the casing comprising a bottom wall and a hinged cover detachably engaged with the frame structure and attached thereto without the use of pins, screws or other fastening devices with the idea of lessening the cost of manufacture.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a side elevational view of a vanity case constructed in accordance with the present invention, the same being illustrated as of comparatively thin construction and of substantially elliptical formation;

Figure 2 is an end elevational view of the device; Figure 3 is a side elevational view with the cover and mirror raised to open position and showing the spring connection between the hinged cover and hinged mirror;

Figure 4 is a top plan view of the vanity case with the cover and mirror in opened position;

Figure 5 is a vertical longitudinal sectional view taken on line 5—5 of Figure 4;

Figure 6 is a vertical cross-sectional view taken on line 6—6 of Figure 3;

Figure 7 is a side elevational view of the bottom wall and hinged cover of the vanity case removed from the frame structure thereof; and

Figure 8 is a sectional view similar to Figure 5 showing the cover in closed position and the

mirror tightly engaged with the powder receptacle.

Referring more in detail to the accompanying drawing, the vanity case is of relatively thin construction and substantially elliptical in side elevation, comprises a frame having side bars 10 and connecting end bars 11 and 12 that are set slightly inwardly of the sides and ends of the side bars 10 with the outer sides of the connecting end bars 11 and 12 inclined upwardly as at 13 and 14 10 respectively. The opening afforded by the side bars 10 and connecting end bars 11 and 12 accommodates the mounting of the open topped powder receptacle 15 disposed adjacent the end connecting bar 11 and the paste rouge receptacle 15 16 disposed adjacent the end connecting bar 12. The receptacle 16 is provided with a hinged cover 17 opening transversely of the vanity case. A mirror 18 is hinged as at 19 adjacent the end connecting bar 12 and is adapted to overlie the cover 17 of the paste rouge receptacle 16 and the open topped powder receptacle 15 to provide a closure for the powder receptacle.

The enclosing casing of the vanity case is shown in detail in Figure 7 and comprises a bottom wall 20 and a top wall or cover 21 hinged to the bottom wall as at 22. The enclosing casing that is of a thickness comparable with the insetting of the end connecting bars 11 and 12 so as to lie substantially flush with the side bars 10 of the vanity case. The bottom wall 20 and hinge cover 21 of the enclosing casing are of elliptical formation and the free edge of the bottom wall 20 is flanged as at 23 for engagement with the upwardly inclined edge 13 of the end connecting bar 35 11. The enclosing casing is inherently resilient and when the flange 23 is engaged with the end connecting bar 11 as stated, the hinged connection 22 between the bottom wall 20 and cover 21 of the enclosing casing stops over the outer 40 end of the end connecting bar 12 for engagement with the inclined side edge 14 thereof, and cooperates with flange 23 for retaining the enclosing casing on the frame structure of the vanity case. The free edge of the hinged cover 45 21 carries a spring clip 24 that is adapted to be extended over the flanged end 23 of the bottom wall 20 as illustrated in Figures 1, 2 and 7 for retaining the inclosing casing in closed condition.

An arched leaf spring 25 is anchored at one end 50 as at 26 to the upper side of the mirror 18 adjacent its free swinging end, the arched leaf spring 25 being directed toward the hinged cover 21 and extends through a guide loop 27 depending from the cover intermediate its ends. It will be 55

readily understood that when the hinged cover 21 is moved to an open position as illustrated in Figures 3 and 5, the mirror 18 is automatically raised to its operative position for use and at the 5 desired angle. When the cover 21 is closed, the mirror 18 is simultaneously moved to its closed position overlying the powder receptacle 15 and pressure is exerted by the cover 21 on the arched leaf spring 25 to effect a tight connection between the mirror 18 and powder receptacle to 10 prevent the escape of powder when the vanity case is out of use.

From the above detailed description of the invention, it is believed that the construction and 15 operation thereof will at once be apparent, and while there is herein shown and described the preferred embodiment of the invention, it is nevertheless to be understood that minor changes may be made therein without departing from the 20 spirit and scope of the invention as claimed.

I claim:—

1. In a vanity case, a bottom wall and a hinged cover, a powder receptacle in the case, a hinged mirror in the case adapted to form a closure for 25 the powder receptacle, and a resilient connection between the cover and mirror to effect tight closure of the mirror on the powder receptacle and elevation of the mirror to a position for use upon opening movement of the cover.

30 2. In a vanity case, a bottom wall and a hinged cover, a powder receptacle in the case, and a hinged mirror in the case adapted to form a closure for the powder receptacle, a leaf spring anchored to the upper side of the mirror, a slide connection between the mirror and cover whereby the mirror is raised to a position for use when the cover is opened and the spring being arched outwardly of the mirror for compressive contact by the cover to effect tight closure of the mirror 35 on the powder receptacle.

40 3. In a vanity case, a bottom wall and a hinged cover, a powder receptacle in the case, a hinged mirror in the case adapted to form a closure for the powder receptacle, the case including a frame 45 structure having side and end bars, the opposite ends of the bottom wall being clampingly engaged with the end bars and separable from the frame structure and a spring clip on the free end of the cover for overlapping clamping engagement with the free end of the bottom wall and adjacent end bar.

45 4. In a vanity case, a bottom wall and a hinged cover, a powder receptacle in the case, a hinged mirror in the case adapted to form a closure for the powder receptacle, and operatively associated with the cover whereby the same is raised to a position for use upon opening movement of the cover, the case including a frame structure having side and end bars, the opposite ends of the bottom wall being clampingly engaged with the end bars and separable from the frame structure and a spring clip on the free end of the cover for overlapping clamping engagement with the free end of the bottom wall and adjacent end bar.

50 5. In a vanity case, a bottom wall and a hinged cover, a powder receptacle in the case, a hinged mirror in the case adapted to form a closure for the powder receptacle, and a resilient connection between the cover and mirror to effect tight closure of the mirror on the powder receptacle and elevation of the mirror to a position for use upon opening movement of the cover, the case including a frame structure having side and end bars, the opposite ends of the bottom wall being clamped

55 6. In a vanity case, a bottom wall and a hinged cover, a powder receptacle in the case, and a hinged mirror in the case adapted to form a closure for the powder receptacle, a leaf spring anchored to the upper side of the mirror, a slide connection between the mirror and cover whereby the mirror is raised to a position for use when the cover is opened and the spring being arched outwardly of the mirror for compressive contact by the cover to effect tight closure of the mirror on the powder receptacle, the case including a frame structure having side and end bars, the opposite ends of the bottom wall being clampingly engaged with the end bars and separable from the frame structure and a spring clip on the free end of the cover for overlapping clamping engagement with the free end of the bottom wall and adjacent end bar.

60 7. In a vanity case, a bottom wall and a hinged cover, a powder receptacle in the case, a hinged mirror in the case adapted to form a closure for the powder receptacle, the casing including a frame structure having side and end bars, with the end walls set inwardly of the side bars and forming a support for the powder receptacle, the opposite ends of the bottom wall being clampingly engaged with the end bars and separable from the frame structure and a spring clip on the free end of the cover for overlapping clamping engagement with the free end of the bottom wall and adjacent end bar.

65 8. In a vanity case, a bottom wall and a hinged cover, a powder receptacle in the case, a hinged mirror in the case adapted to form a closure for the powder receptacle, and operatively associated with the cover whereby the same is raised to a position for use upon opening movement of the cover, the case including a frame structure having side and end bars, with the end walls set inwardly of the side bars and forming a support for the powder receptacle, the opposite ends of the bottom wall being clampingly engaged with the end bars and separable from the frame structure and a spring clip on the free end of the cover for overlapping clamping engagement with the free end of the bottom wall and adjacent end bar.

70 9. In a vanity case, a bottom wall and a hinged cover, a powder receptacle in the case, a hinged mirror in the case adapted to form a closure for the powder receptacle, and a resilient connection between the cover and mirror to effect tight closure of the mirror on the powder receptacle and elevation of the mirror to a position for use upon opening movement of the cover, the case including a frame structure having side and end bars, with the end walls set inwardly of the side bars and forming a support for the powder receptacle, the opposite ends of the bottom wall being clampingly engaged with the end bars and separable from the frame structure and a spring clip on the free end of the cover for overlapping clamping engagement with the free end of the bottom wall and adjacent end bar.

75 10. In a vanity case, a bottom wall and a hinged cover, a powder receptacle in the case, and a hinged mirror in the case adapted to form a closure for the powder receptacle, a leaf spring anchored to the upper side of the mirror, a slide connection between the mirror and cover whereby the mirror is raised to a position for use when the cover is opened and the spring being arched outwardly of the mirror for compressive contact by the cover to effect tight closure of the mirror on the powder receptacle, the case including a frame structure having side and end bars, the opposite ends of the bottom wall being clamped

by the mirror is raised to a position for use when the cover is opened and the spring being arched outwardly of the mirror for compressive contact by the cover to effect tight closure of the mirror 5 on the powder receptacle, the case including a frame structure having side and end bars, with the end walls set inwardly of the side bars and forming a support for the powder receptacle, the opposite ends of the bottom wall being clampingly 10 engaged with the end bars and separable from the frame structure and a spring clip on the free end of the cover for overlapping engagement with the free end of the bottom wall and adjacent end bar.

11. In a device of the character described, a 15 case including a frame structure having side and end bars, a bottom wall and a hinged cover mounted on the frame structure, the opposite ends of the bottom wall being overlappingly en-

gaged with the end bars and separable from the frame structure and a spring clip on the free end of the cover for overlapping clamping engagement with the free end of the bottom wall and adjacent end bar.

12. In a device of the character described, a case including a frame structure having side and end bars, a bottom wall and a hinged cover mounted on the frame structure, with the end walls set inwardly of the side walls, the opposite 10 ends of the bottom wall being overlappingly engaged with the end bars and separable from the frame structure and a spring clip on the free end of the cover for overlapping clamping engagement with the free end of the bottom wall 15 and adjacent end bar.
